(57) **CLAIM**

The ornamental design for an earphone accessory, as shown and described.

DESCRIPTION

FIG. 1 is a top, front, right perspective view of a right-side earphone accessory showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a bottom, rear, left perspective view thereof;

FIG. 9 is a an alternate configuration of FIG. 1 shown with exemplary environment;

FIG. 10 is a top, rear, right perspective view of a left-side earphone accessory showing an alternate embodiment of my new design;

FIG. 11 is a front view thereof;

FIG. 12 is a rear view thereof;

FIG. 13 is a right side view thereof;

FIG. 14 is a left side view thereof;

FIG. 15 is a top view thereof;

FIG. 16 is a bottom view thereof;

FIG. 17 is a bottom, rear, left perspective view thereof; and, FIG. 18 is an alternate configuration of FIG. 10 shown with exemplary environment.

The broken lines immediately adjacent to the shaded area define the bounds of the claimed design and form no part thereof. The broken lines depicting the remainder of the earphone accessory show features that form no part of the claimed design.

1 Claim, 18 Drawing Sheets
